UNITED STATES PATENT OFFICE.

HANNAH MAY NORTH, OF OSCODA, MICHIGAN.

ATTACHMENT FOR IRONING-BOARDS.

1,016,848.

Specification of Letters Patent.

Patented Feb. 6, 1912.

Application filed October 1, 1910. Serial No. 584,906.

To all whom it may concern:

Be it known that I, HANNAH MAY NORTH, a citizen of the United States, residing at Oscoda, in the county of Iosco and State of Michigan, have invented new and useful Improvements in Attachments for Ironing-Boards, of which the following is a specification.

The invention relates to an improvement 10 in ironing boards, being particularly directed to adjustable means supporting articles of unusual length or width during ironing.

The main object of the present invention 15 is an improvement including a sliding frame adjustably mounted with relation to the ironing board, which frame is adapted to be projected to any desirable length beyond the edge of the board to provide for supporting the article being ironed.

The invention will be described in the following specification, reference being had particularly to the accompanying drawings, in which:—

25 Figure 1 is an inverted plan view of an ironing board having the improvement attached. Fig. 2 is an enlarged sectional view on the line 2—2 of Fig. 1. Fig. 3 is an end view showing the notches in the bar of my devices.

Referring particularly to the accompanying drawings, 1 represents an ironing board of any usual or preferred construction, 2 is a sliding frame designed for adjustment with relation to one edge of said board, said frame being preferably constructed of wire and formed to provide a U-shape, having a supporting bar 3, of a length somewhat less than the length of the 30 ironing board and having side bars 4 slidably mounted in bearing blocks 5 secured to

the under surface of the board at appropriate points. The inner terminals of the bars 4, are bent laterally to prevent the accidental disconnection of the frame with 45 the ironing board. One or both of the bars 4, are formed to provide a series of locking notches 6, and there are secured on the under side of the board catches 7 in the form of a spring pressed lever, in the use of which 50 the frame may, as will be obvious, be held at any desired length of projection beyond the edge of the board.

In use as when ironing table cloths, curtains or the like, the frame may be projected at any desired extent and in such projected position serves as a support for the extra length or width of the material and keeps such material from off the floor.

The improvement may be readily applied 60 to any ironing board, and in use will prevent the possibility of articles being ironed from reaching the floor during the ironing process.

Having thus described the invention, what I claim as new is:—

65 The combination of an ironing board, a U-shaped frame provided with a series of notches and having the ends thereof bent laterally outward, bearing blocks secured to the said ironing board and having the said frame slidably mounted therein, and spring-pressed catches secured to the said ironing board and adapted to engage the notches of the said frame to adjust the frame relatively to the ironing board. 70

75 In testimony whereof I affix my signature in presence of two witnesses.

H. MAY NORTH.
